CLAIM

The ornamental design for a container closure, as shown and described.

DESCRIPTION

FIG. 1 is a top, front, and right side perspective view of a container closure;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines of the container closure body portion shown in the drawings are included for the purpose of illustrating environmental structure and form no part of the claimed design.
